TEMPORARY TIE SUPPORT

Earl E. Hayton, Detroit, Mich.

Application October 14, 1943, Serial No. 506,287

3 Claims. (Cl. 223—111)

1

This invention relates to means for facilitating manipulation of a tie between the folds of a shirt collar during the fashioning of the knot and contemplates merely the temporary mechanical aid to such procedure; as distinguished from the provision of permanent or semi-permanent collar supports, stiffeners, or frames such as have been hitherto suggested, more especially in connection with soft collars, as a means of maintaining shape in the collar while being worn, as well as a support for the portion of the tie between the folds of the collar.

The object of the invention is to provide an extremely simple device which may be temporarily slid in between the folds of the collar together with that portion of the tie which is to be pulled backward and forward between such folds during the tying operation. The device is intended to insure free running clearance of the tie between the folds of the collar and prevents the binding which is so commonly met with when the tie is ordinarily being manipulated, especially for the first time within the folds of a newly laundered collar. As soon as the required manipulation of the tie has been effected it is intended that the supporting and spacing device shall be removed as having served its sole purpose.

A further object of the invention is to provide a band of thin flexible material bent, or which may subsequently be bent, to the general circular form of the collar and shaped to provide a clearance space between said band and the inner fold of the collar when inserted between the folds of said collar, said band having means at its lower edge for receiving and supporting the lower margin of the tie during its manipulation and said band being also formed for free withdrawal from between the folds of the collar after the required manipulation of the tie has been effected.

Still further objects subsidiary to the aforesaid objects or resulting from the construction or operation of the invention as it may be carried into effect will become apparent as the said invention is hereinafter further disclosed.

In carrying said invention into effect, I may utilize the novel construction and arrangement illustrated, by way of example, in the accompanying drawing, wherein:

Figure 1 is a perspective view of the temporary tie support embodying the said invention, part of the collar to which it is applied being indicated, and;

Figure 2 is a cross section of the same.

Similar characters of reference indicate similar parts in both figures in the drawings.

2

10 indicates the collar of the shirt having the usual inner and outer folds 11 and 12 between which the narrow elongated portion 16 of the tie runs and is usually required to be manipulated backwards and forwards during your tying of the knot in the tie as is well understood, and this manipulation is very frequently rendered quite difficult due to the trapping of this portion of the tie between the folds of the collar with consequent binding and friction, sometimes to such an extent that the collar or the tie, or both, are unnecessarily stretched or distorted out of shape to the detriment of both material and appearance.

To obviate the aforesaid difficulties, I provide a 15 flexible band 13 of any suitable material such as plastic, for instance, so shaped as to provide a space 14 between its inner surface and the opposed surface of the fold 11 of the collar, when the said band is inserted between the folds of the said collar, and 15 represents inwardly and upwardly turned supporting means for the tie, which means may be in the form of a bead notched or interrupted throughout its length, as at 16, so that it will not interfere with the flexibility of the band as will be readily understood. 20 Said notching of this bead may be dispensed with in cases where any great amount of flexibility in the band is not desired, such as when the band is already moulded or fashioned to the approximate size of the collar with which it is intended to be used.

I prefer to make a cross sectional form of the band arcuate as shown in Figure 2 or of such equivalent cross section as will provide the necessary tie space, the upper edge of the said band being, however, disposed substantially above the said bead 15 so that it extends inwardly somewhat of the medial annular portion of the band. I may also make the upper portion of the band 30 13 thickened, as at 17, to promote the spacing of the collar parts 11 and 12.

It is also desired that the inner surface of the said band merge into the inner upper edge thereof in a substantially continuous manner so that 35 when it is desired to remove the band from the collar, after manipulation of the tie has been completed, it may be easily slid downwardly over the encircling band of the tie within the collar 40 and thereby removed without disturbing the tie or distorting the collar to any undesirable degree.

In its preferred form, as shown in Figure 2, the tie band 16a is merely supported by the bead 15 while the said band is being positioned between 45 the folds of the collar. During the tying opera-

tion, however, the band of the tie will assume the dotted position free of the said bead 15 as shown.

This invention may be developed within the scope of the following claims without departing from the essential features of the said invention and it is desired that the specification and drawings be read as being merely illustrative and not in a limited manner as to precise design.

What I claim is:

1. A device of the type described, comprising a flexible elongated band adapted for temporary insertion and complete and free positioning between a tie and the outer fold of a shirt collar, said flexible band being bowed transversely throughout its medial portion for the entire length thereof to hold the said outer fold of the shirt collar in spaced apart relation and form an unrestricted slideway for the tie band, said slideway extending substantially throughout the length of the collar and opening towards the inner fold of the collar to facilitate removal of the band.

2. A device of the type described, comprising a flexible elongated band adapted for temporary insertion and complete and free positioning between a tie and the outer fold of a shirt collar to maintain said tie and outer fold in spaced relation during the positioning and adjusting of the tie, said flexible band having an inwardly and upwardly turned tie supporting bead along its lower edge extending substantially throughout the length of the collar for receiving the lower edge of the tie band to facilitate insertion of the same between the folds of said collar, and said bead being relatively narrow whereby the neck band portion of the tie when tightened will move out of said bead and allow easy removal of the flexible band.

3. A device of the type described, comprising a flexible elongated band adapted for temporary insertion and complete and free positioning between a tie and the outer fold of a shirt collar to hold said tie and outer fold separated during the positioning and adjustment of the tie, said flexible band being shaped to provide an inwardly and upwardly turned bead along its lower edge extending substantially throughout the length of the collar to facilitate easy insertion of a tie band between the folds of said shirt collar, and the upper edge of said flexible band being directed inwardly throughout its neck encircling length to a point substantially above the inner edge of said bead and presenting a surface capable of being freely withdrawn downwardly over a positioned tie.
